UNITED STATES PATENT OFFICE.

EMANUEL CAVIGELLI, OF ST. MARGARETHEN, NEAR MUNCHWILEN, SWITZERLAND,
ASSIGNOR TO THE FIRM SCHWEIZ GESELLSCHAFT FÜR TULLINDUSTRIE A.-G., OF
MUNCHWILEN, SWITZERLAND.

PLAIN-NET LOOM.

Application filed March 25, 1921. Serial No. 455,513.

(GRANTED UNDER THE PROVISIONS OF THE ACT OF MARCH 3, 1921, 41 STAT. L., 1313.)

To all whom it may concern:

Be it known that I, EMANUEL CAVIGELLI, a citizen of the Republic of Switzerland, residing at St. Margarethen, near Munchwilen, Thurgau, Switzerland, have invented 5 certain new and useful Improvements in Plain-Net Looms (for which applications for patents have been filed in the following countries: Switzerland, Nov. 22, 1919, 10 Patent No. 88,738; Germany, December 4, 1919, Patent No. 333,529; England, Nov. 22, 1920, appln. No. 32,927/20; and France, Jany. 5, 1921, application No. 138/295); and I do hereby declare the following to 15 be a clear, full, and exact description of the invention, such as will enable others skilled in the art to which it appertains to make and use the same, reference being had to the accompanying drawings, and to letters 20 or figures of reference marked thereon, which form a part of this specification.

This invention relates to improvements in plain net looms and particularly to an automatic fabric winding device for tulle looms. Automatic fabric winding devices 25 are known which produce a gradual increase of the warp tension by an increase in the speed of rotation of the card beam and on which rests the cloth beam, frictionally 30 driven thereby. This increase of warp tension is effected by a gradual and uniform increase in the feed movement of the card beam, which is obtained by a movement or shifting of the point of engagement of a 35 driving rod operating the feed lever. In known devices of this kind, the feed movement of the card beam is produced by means of a feed lever which is operated by a vertically reciprocating driving rod. The move- 40 ment of the point of engagement of the driving rod operating the feed lever, required for shifting it, is derived from the rotary motion of the card beam through known gears. In the device according to 45 the invention, the movement required for moving the point of engagement of the feed lever, is derived from the up and down movement of the driving rod, and is therefore independent of the rotation of the card beam.

To that end, a coupling rod connected to the driving rod, is provided with a stop

which during the upward movement acts on a vertical rod connected to a lever, and the said rod in co-operation with lever, pawl 55 and ratchet wheel and a worm wheel gear, produces the movement or shifting of the point of engagement of the feed lever. In plain net looms besides the vertical warp threads and horizontal weft threads, there 60 are used threads that in the finished fabric are inclined 30° upward and threads that are inclined 30° downward. The inclined threads with the warp and weft form a hexagonal ground figure when the tension is on 65 the threads.

The inclined threads are provided from a spool system, and the greater the number of threads being supplied from a single spool the smaller must be the diameter of the 70 spool; consequently the greater is the pull required to turn the spool. The tension of the weft threads therefore becomes greater as the process proceeds, and this will produce a distortion of the ground figure if 75 care is not taken to simultaneously increase the tension on the warp. This I do by increasing the draft on the warp by increasing the speed of the rough-surfaced card beam, by a mechanism I shall now describe 80 in detail.

A construction according to the invention is illustrated by way of example in the accompanying drawings, in which

Figure 1 shows a front elevation,

Figure 2 a side elevation and

Figure 3 a plan, partly in section on the line I—I of Figure 1, and

Figure 4 a general arrangement of the plain net loom provided with the device according to the invention.

The working of the construction according to the invention will be explained simultaneously with the description of its single parts.

The finished fabric is wound by a card beam 1, the feed movement of which is for instance derived from a cam disc 42 mounted on the driving shaft 43 by the interposition of a swinging lever 44 or it may be derived from any oscillating driving part of the loom and transmitted to a vertically reciprocating driving rod 2. The driving rod 2 is connected by a pin 3 to a lever 4 which

85

100

swings about a pin 6 of the machine frame. The oscillation of the lever 4 is transmitted through a pin 8, coupling rod 7 and a pin 9 to a link lever 10 rigidly connected to a 5 ratchet gear casing 11 rotatably mounted on a spindle 12. In the casing 11 are provided thirty one pawls 13 which are mounted in a loosely rotatable manner on pins 14 and pressed by suitably arranged 10 springs against a ratchet wheel 15 provided with thirty two teeth. The pawls are so arranged relatively to the teeth that only one pawl is always in complete engagement with a tooth interval of the wheel 15. An 15 advance of the wheel 15 accordingly takes place when the lever 10 is oscillated to the extent of $1/31$ of the pitch. For preventing the wheel from turning back relatively to the casing, in the casing part 16 are also 20 provided thirty one spring controlled pawls loosely rotatable on pins 17. The casing 16 is secured by means of screws 19 to a stand 20 secured to the machine frame 5. The movement is transmitted to the card 25 beam by the ratchet wheel 15 which is keyed to the spindle 12, which carries a worm 21 engaging with a worm wheel 22 keyed to a spindle 23 which carries the card beam 1. On the coupling rod 7 is provided a stop 24 30 which can be secured in different vertical positions on the coupling rod 7 and which during the upward movement, presses upwards a rod 25. This movement is transmitted by a bolt 26 to a lever 27, the loose 35 centre of rotation of which is situated on a spindle 28, and by a pawl 29 to a ratchet wheel 30 which is turned to the extent of at least one tooth division. The rotation of the ratchet wheel 30 is transmitted by a worm 40 31 also firmly secured to the spindle 28, and by a worm wheel 32 meshing with it, to a spindle 33 mounted in a stand 20. On the screw threaded spindle 33, the movement of the ratchet wheel 30 moves towards the machine 45 a double L-shaped guide 34 secured to the nut travelling on the spindle. In the guide 34 travels up and down a slide block 35 connected to the coupling rod 7, in accordance with the up and down movements 50 of the coupling rod 7. During the inward movement of the guide 34 caused by the ratchet wheel 30, the pin 9 moves in the link lever 10 towards the machine, and in that way the feed movement of the wheel 55 15 is increased. To the gradual movement or shifting of the coupling rod 7 towards the machine corresponds, with the invariable stroke of the driving rod 2, a gradually and uniformly increased speed of rotation of the card beam.

A scale 36 is arranged on the stand 20 above the spindle 33, on which scale is set the guide 34 at the beginning of the working period. This is done by disengaging 60 65 the pawl 29 from the ratchet wheel 30 and

by turning a crank 37 in the direction opposite to the feed or advance, until an index 38 provided on the guide 34, reaches an agreed point of the scale. With the assistance of the scale 36, the attendant can 70 see whether the device according to the invention is working correctly.

The scale 39 provided on the lever 4, makes it possible to read the extent of movement of the centre of rotation 8 by means of the 75 spindle 40 and hand wheel 41. In the case of finer qualities of plain net fabrics, the gradual increase in the advance movement of the card beam must be of course smaller than in the case of coarser fabrics, so that 80 in the case of finer fabrics, the pin 8 is set towards the beginning of the scale 39, and in the case of coarser fabrics, towards the end of the same.

By moving the stop 24 along the coupling 85 rod 7, the movement of the point of engagement 9 on the feed lever 10 can be influenced to the widest possible extent.

With this device tulle may be manufactured with different widths of mesh on one 90 and the same machine, without changing the stroke of the driving rod 2.

I claim:

1. In an automatic fabric winding device 95 for plain net looms, the combination of means comprising a feed lever operatively connected to the card beam and adapted to effect a feed motion of the latter, an oscillating member engaging with said feed lever the point of engagement being displaceably 100 arranged along said feed lever, means for effecting a gradual displacement of said point of engagement and thereby a gradual increase of the feed motion, a member for operating said means and means interposed 105 between said oscillating member and a driving part of the loom to impart an oscillating movement to the former.

2. In an automatic fabric winding device 110 for plain net looms, the combination of means comprising a feed lever operatively connected to the card beam and adapted to effect a feed motion of the latter, an oscillating member engaging with said feed lever the point of engagement being displaceably 115 arranged along said feed lever, a guide provided for said point of engagement, a lever adapted to effect a displacement of said guide towards the fulcrum of said feed lever by the interposition of a gear, a stop provided on said oscillating member and co-acting with said lever, and means interposed 120 between said oscillating member and a driving part of the loom to impart the oscillating movement to the former.

3. In an automatic fabric winding device 125 for plain net looms, the combination of means comprising a feed lever operatively connected to the card beam and adapted to effect a feed motion of the latter, an oscil- 130

lating member engaging with its upper end with said feed lever, the point of engagement being held in a guide, a lever adapted to effect a displacement of said guide to 5 wards the fulcrum of said feed lever for gradually increasing the feed motion by the interposition of a pawl, a ratchet wheel, worm wheel gear and screw threaded spindle, a stop provided on said oscillating mem- 10 ber and coacting with said lever, a swingably mounted lever to which the lower end of said oscillating member is pivoted, and a driving rod interposed between a driving part of the loom and said swingably mounted lever for imparting an oscillating move- 15 ment to the latter and thus to the oscillating member.

4. In an automatic fabric winding device for plain net looms, the combination of 20 means comprising a feed lever operatively connected to the card beam and adapted to effect a feed motion of the latter, an oscillating member engaging with its upper end with said feed lever, the point of engagement being held in a guide, a lever adapted to effect a displacement of said guide to 25 wards the fulcrum of said feed lever for gradually increasing the feed motion through the intermediary of a gear, a stop provided 30 on said oscillating member and coacting with said lever, a swingably mounted lever to which the lower end of said oscillating member is pivoted, means to displace said pivot along a scale provided on said swing- 35 ably mounted lever for altering the feed motion to correspond to a desired alteration of mesh of the tulle fabric, and a driving rod interposed between a driving part of the loom and said swingably mounted lever 40 for imparting an oscillating movement to the latter and thus to the oscillating member.

5. In an automatic fabric winding device

for plain net looms, the combination of 45 means comprising a feed lever operatively connected to the card beam and adapted to effect a feed motion of the latter, an oscillating member engaging with its upper end with said feed lever, the point of engagement being held in a guide, a lever adapted to 50 effect a displacement of said guide to wards the fulcrum of said feed lever for gradually increasing the feed motion through the intermediary of a gear, a stop provided on said oscillating member and coacting with said lever and adapted to be adjusted along said oscillating member for altering the feed motion, a swingably mounted lever to which the lower end of said oscillating member is pivoted, means to displace said 55 pivot along a scale provided on said swing- ably mounted lever for altering the feed motion to correspond to a desired alteration of the mesh of the tulle fabric, and a driving rod interposed between a driving part of the 60 loom and said swingably mounted lever for imparting an oscillating movement to the latter and thus to the oscillating member.

6. In an automatic fabric winding device 65 for plain net looms, a fabric beam, a ratchet wheel secured thereto, a large number of pawls acting thereon only one of which is in full engagement with the said wheel at any one time, a pawl carrier surrounding said wheel, a lever connected to the carrier, 70 a reciprocable rod having sliding connection with the lever, a lever pivoted at one end to a fixed part and adjustably connected with the end of said rod, mechanism to progressively shorten the effective length of the first 75 lever and an adjustable stop on said rod to actuate said mechanism.

In testimony that I claim the foregoing as my invention, I have signed my name.

EMANUEL CAVIGELLI.
